UNITED STATES PATENT OFFICE.

HAROLD EDGAR FOX, OF NEWTOWN, SYDNEY, NEW SOUTH WALES, AUSTRALIA.

SPRING ROLLER-BLIND.

1,342,017.

Specification of Letters Patent.

Patented June 1, 1920.

Application filed September 4, 1919. Serial No. 321,726.

To all whom it may concern:

Be it known that I, HAROLD EDGAR FOX, subject of the King of Great Britain and Ireland, resident of 18 King street, New- 5 town, Sydney, in the State of New South Wales, Commonwealth of Australia, have invented certain new and useful Improvements in Spring Roller-Blinds, of which the following is a specification.

10 This invention relates to roller blinds of the type in which a spring contained within the roller is tensioned by drawing down the blind and by reaction rewinds the blind when controlling pawls are released.

15 It sometimes happens that if a blind is released and gains considerable momentum, the controlling pawls do not operate and the blind races.

20 The purposes of this invention are to provide simple and effective means for preventing such racing, but permitting the actuation of the blind at reasonable and normal speed.

25 The invention consists in providing check- ing means comprising one or more spring control pawl-catches and associated detent or detents with which said catch or catches is or are caused by centrifugal action to engage when the roller attains excessive 30 speed in rolling up the blind, and by so doing check its rotation. To release the pawl- catch or catches, a slight downward pull on the blind disengages it or them from the detent or detents, and it or they is or are 35 returned to normal inoperative position by spring pressure. The invention also consists in the provision of a cylindrical cap fitted on one end of the roller and over the pivot pin thereat, said cap carrying the pawl- 40 catch or catches; and in the provision of a cylindrical sleeve carried by the roller-supporting bracket, and within which one end of said cap is housed, said sleeve carrying the detent or detents. The invention further 45 consists in rotatably mounting said cylindrical sleeve on the bracket and providing a controlling spring therefor, so that resil- iency is given to the detent and too sudden stoppage of the roller is avoided.

50 To fully explain the invention and the manner in which it may be employed, reference will now be made to the accompanying drawings in which—

Figure 1 represents my invention applied 55 to end of a spring blind roller, said end be-

ing that at which the non-rotating pivot pin exists.

Fig. 2 represents the end of the roller with cap carrying the checking means fitted thereto; and also shows separately the cylindrical 60 sleeve attached to the bracket, said sleeve being partly broken away to show more clearly the internal arrangements.

Fig. 3 represents the end of the roller and the cap removed therefrom, disclosing the 65 ordinary controlling pawls, with which my invention does not interfere, but is additional to.

Fig. 4 is a sectional plan view of the construction shown in Fig. 1.

Fig. 5 is a vertical sectional elevation on line 5, 5 of Fig. 4.

Fig. 6 is a perspective view of a modified form of my invention.

In the drawings reference numeral 8 indicates the roller on the end of which is fitted a cap 9, having a closed end 10 apertured to take over the pivot pin 11. Said cap covers the ordinary control pawls 12, 12 housed in the recessed end of the usual cap pieces 13. 75 80

On the closed end of the cap 9 are carried a pair of pawl-catches 14, 14, pivoted respectively on screws 15, 15 and normally held in inoperative position by leaf springs 16, 16 is sufficient to resist centrifugal force and 85 maintain the pawl-catches in inoperative position unless the speed of the roller becomes excessive.

Referring to Figs. 1 to 5 inclusive, the bracket 18 is brazed or otherwise attached 90 to a flanged disk 19 centrally forming a hollow boss 20 which is slotted as at 21 to receive the pivot pin 11 of the roller (see Fig. 4). On the flanged disk is rotatably mounted a cylindrical sleeve 22 held on the said 95 disk by having an annular inset as at 23 engaging one side of the flange, and by lugs 24, 24 integral with the sleeve and bent over the other edge of the flange. Internally the sleeve carries a pair of detents 25, 25. The 100 end of cap 9 enters the sleeve 22 when the pivot pin 11 engages its bearing slot 21, the pawl-catches 14, 14 alining with detents 25, 25 and engaging same when the speed of the roller is such as to create sufficient centrifugal force to cause said catches to move outwardly. At reasonable speed the pawl-catches are held inwardly by their springs and do not engage the detents.

It will be noted that engagement of the 110

pawl-catches with the detents only occurs when the blind is rolled up at excessive speed; the rounded construction of the swinging ends of the pawl-catches enables 5 same to pass the detents without engagement when the blind is drawn down at any speed. As before stated the sleeve 22 is rotatably mounted on the disk 19 and the engagement of the pawl-catches with the 10 detents would tend to rotate it. This tendency is resisted by a spring 26, which gradually absorbs the shock and brings the roller to rest. Said spring 26 is connected to a lug 15 27 on the sleeve and to any convenient fixture such as the bracket 18.

Referring to Fig. 6, the construction is the same as before described except as regards the flanged disk and sleeve. These latter elements are omitted and the bracket 20 18 is of more ordinary construction, being however terminally bent to provide a detent 28 with which either of the pawl catches 14, 14 engage under the conditions before stated. It is to be understood that the 25 springs 15, 15 exert sufficient force on the pawls to resist the centrifugal tendency of the latter when the roller rotates at a normal speed. It is also to be understood that the 30 checking means herein described are in addition to and in no way relate to the usual controlling pawls provided for holding the blind at any desired elevation.

What I claim and desire to secure by Letters Patent is:—

35 1. The combination with a spring blind-
roller and a supporting bracket therefor of
means for preventing racing of said roller
in a direction to wind up the blind, comprising
a pawl-catch pivoted on the end of 40
said roller, a spring normally retaining said
pawl catch in inoperative position, and a de-
tent carried by said bracket and with which

said pawl engages when the speed of the 45 roller in the direction specified creates sufficient centrifugal force to cause said pawl-
catch to overcome the spring pressure and move outwardly.

2. The combination with a spring blind roller and a supporting bracket therefor of 50 checking means for preventing the racing of the roller in a direction to wind up the blind, comprising a cap fitted on one end of the roller and apertured to take over the pivot pin of said roller, a pawl-catch pivoted on the end of said cap, a spring normally re- 55 taining said catch in inoperative position, a detent carried by said bracket and with which said pawl engages when the roller attains excessive speed in the direction specified and centrifugal force causes the pawl- 60 catch to overcome the pressure of the spring and move outwardly.

3. The combination with a spring blind roller and a supporting bracket therefor of 65 means for preventing racing of said roller in a direction to wind up the blind, and comprising a cap fitted on one end of the roller and apertured to take over the pivot thereof, a pawl-catch pivoted on the end of said cap, a spring normally retaining said 70 catch in inoperative position, a cylindrical sleeve housing the end of the cap with the roller and rotatably mounted on the supporting bracket, a spring resiliently check- 75 ing the rotation of said sleeve, and in said sleeve a detent with which catch engages when the roller attains excessive speed in the direction indicated and centrifugal force causes said catch to overcome the pressure of its retaining spring and move outwardly. 80

Signed at Sydney, New South Wales, this 23d day of July, 1919.

HAROLD EDGAR FOX.
